UNITED STATES PATENT OFFICE.

CARL H. WHITNEY, OF CRAIG, NEBRASKA.

GAME.

Application filed November 17, 1923, Serial No. 675,311. Renewed May 22, 1925.

To all whom it may concern:

Be it known that CARL H. WHITNEY, a citizen of the United States, residing at Craig, in the county of Burt and State of Nebraska, has invented certain new and useful Improvements in Games, of which the following is a specification.

This invention is an improvement in games, and with respect to its more specific features, to games of the ball and pocket type.

An object of the invention is to provide a new and improved construction of board, having pockets or stalls for receiving game-pieces, and hazards to hinder the entrance of the pieces.

Another object is to provide a board having means to support the same in playing position detachably connected with the board, to permit the parts to be packed flat and in small compass.

Another object is to provide a board wherein the hazards, constituted by the partitions between the pockets or stalls, are movable, so that the hazards of any selected pocket may be increased or diminished.

Another object is to provide a game which may be cheaply manufactured, and sold at a low price.

Another object is to provide a game which may be played in many different ways, in accordance with the skill and capacity of the player, thus to be interesting to adults or to children.

With these and other objects in view, the invention consists in the construction and novel combination of parts fully described hereinafter, illustrated in the accompanying drawings, and pointed out in the appended claims; it being understood that various changes in the form, proportion, size and minor details of construction, within the scope of the claims, may be resorted to without departing from the spirit of the invention.

In the drawings forming a part hereof;

Figure 1 is a perspective view of the improved game;

Figure 2 is a rear view of one end of the board;

Figure 3 is an end view;

Figure 4 is a perspective view of a modified form of game-piece;

Figure 5 is a sectional view, showing the connection of the partition bars;

Figure 6 is an end view of an alternate arrangement.

In the present embodiment of the invention, the game includes a board having pockets or stalls, of different value, for receiving game-pieces, and a set or plurality of sets of game-pieces, for cooperating with the pockets.

The board is composed of a strip 1 of sheet material, as for instance card-board, which is supported in a vertical plane by uprights or standards 2, near its ends. Each upright is socketed at its lower end into a base member 3, extending transversely of the strip. The lower ends of the uprights 4 are tapered, as indicated at 4, and the tapered portions enter similarly shaped sockets 5, in the base members. Preferably the sockets 5 are near the middle of the base members, so that the said members extend beyond both faces of the strip.

The strip is secured to the uprights in any suitable manner, in the present instance by tacks 6, and the uprights are held in spaced relation, and the strip is reinforced, by a cross bar 7, which extends longitudinally of the strip at about its center, and is connected to the uprights. The cross bar and the uprights have openings, which are so placed as to register when the cross bar is in proper position, and nails or pins 8 are engaged with the registering openings, one nail or pin at each upright.

The board is designed to be used upon a suitable plane supporting surface, as for instance a floor, table or the like, or even upon the ground when desired, and the pockets or stalls are provided for by partitions, which are loosely connected at one end to the strip, and at the other rest upon the supporting surface for the board.

Each partition is constituted by a bar 9 of suitable material and dimensions, having one end pointed or reduced, as shown at 10, to enter an opening or socket 11, in the strip. These openings may extend into the cross bar to provide a sufficient hold for the bars if desired. From the strip the bars extend forwardly and downwardly, resting at their forward ends on the support for the board. The said ends are movable, so that the entrance to any selected pocket may be enlarged or restricted when desired, thereby to diminish or increase the hazard.

Between each pair of adjacent partition

bars, the strip 1 is provided with an indication 12, of the value of the pocket. The values of the several pockets are unequal, and are increased or diminished without order, to increase the hazards of the game. Such indications in the present instance are numerals, but it is obvious that other indications might be used.

The game-pieces, an embodiment of which is shown in Figure 1, are in one or more sets, each set corresponding in number to the number of pockets. Each piece has a cylindrical or zone shaped surface, forming a circular track 13, on which it may roll. The game-pieces may be spheres, or segments of spheres, and preferably each piece has a plurality of flat or plane surfaces 14, to hinder or prevent rolling, when the piece rests on such surfaces. These surfaces are at opposite sides of the track, and a convenient way of providing for them and the track is to make the pieces in the form of disks, as shown in Figure 1, or in the form of rings as shown in Figure 4. When the pieces are spherical each has an infinite number of tracks, and the hazard is much lessened in one respect, since the piece can not fall upon a flat surface to prevent rolling. In another respect the hazard is increased, since the piece can roll in any direction. The disks 13-14 may be of any suitable material, as may also the rings 15 shown in Figure 4.

The improved board and game-pieces may be of any convenient size. I have found the following dimensions satisfactory. For the board, a length of from sixteen to twenty inches, and a height of eight or nine inches. With a board of this size, the bars 9 will be eight or nine inches long, and the game-pieces will have a diameter of five and a half, or six inches. The board should be spaced above the supporting surface far enough to prevent the game-pieces rolling beneath it. The board may be suitably ornamented, and preferably the name of the game, "Roll-em" is placed thereon, together with any other suitable inscription, as for instance the words "Can" and "You".

The object in playing the game is to obtain as high a score as possible. The game-pieces are rolled toward the board with the object of lodging them in the stalls or pockets. The players, of whom there may be any

number, stand a suitable distance from the board, as for instance six feet, and roll a selected number of pieces, all together or separately as may be agreed upon. The values of the pockets in which pieces are lodged are added together to obtain the score, and any preferred total may be fixed upon by the players.

In the alternate arrangement of Figure 6, the board 16 is supported like that of Figure 1. The stalls or pockets are formed by bars 17, which engage openings in the board and in the strip 18. These bars however extend out from the board, and are supported wholly by the board. They are pointed at both ends, and are reversible, either end being engaged with the openings of the board. The construction is otherwise the same as that of Figure 1.

What I claim as new, is

1. A game including a board having means to support the same in playing position upon a table or the like, and means to provide game-piece receiving pockets at one face of the board, including partitions loosely connected at one end with the board and adapted to rest at the other on the table or other support. 75

2. A game including a board having game-piece receiving pockets, and means to support the board in playing position, including uprights at the ends of the board, and base members to which the uprights are detachably connected extending transversely of the board. 85

3. In games, a board having game-piece receiving pockets, separated by hazards in the form of partitions loosely connected with the board at one end, and adapted to rest at the other on a table or other support for the board, and movable to increase or diminish the hazard at any selected pocket. 90

4. In games, a board having means to support the same in playing position, and game-piece receiving pockets formed by bars loosely connected at one end with the board, and adapted to rest at the other on a table or other support for the board. 100

5. In games, a board including a strip of sheet material having uprights near its ends, a rigid cross bar connecting the uprights, and base members having sockets to receive the lower ends of the uprights. 105

CARL H. WHITNEY.
